[57] CLAIM

The ornamental design for a front wheel well splash guard panel exterior surface, as shown and described.

DESCRIPTION

FIG. 1 is a perspective view of the exterior surface of the front wheel splash guard panel exterior surface of the present invention, it being understood that the broken lines are for illustrative purposes, only, and form no part of the design;

FIG. 2 is a front view of the wheel well splash guard panel exterior surface of FIG. 1;

FIG. 3 is a top view of the wheel well splash guard panel exterior surface of FIG. 1;

FIG. 4 is a forward or left side view of the wheel well splash guard panel exterior surface of FIG. 1;

FIG. 5 is a rear or right side view of the wheel well splash guard panel exterior surface of FIG. 1; and,

FIG. 6 is a bottom view of the wheel well splash guard exterior surface of FIG. 1.

The back of the wheel well splash guard panel exterior surface is not part of the design as it is not visible in use. If it were shown, its outline would be the same as the front view of FIG. 2, although it would have recessed surfaces where the front view has raised surfaces and a projecting rear edge as visible in FIG. 5.
